FIRE EXTINGUISHING PUMP

Henry E. Brandt, North St. Paul, Minn.

Application March 23, 1942, Serial No. 435,789

4 Claims. (Cl. 299—97)

This invention relates to a fire extinguishing device or fire extinguishing pump of the stirrup type. Such devices or pumps are provided as a safety measure in places where there may be a fire and form a quick and convenient means for extinguishing said fire. Said devices have greater importance now in places that might be subject to air raids.

It is an object of this invention to provide a very simple and efficient structure of stirrup pump adapted to be placed in any open-topped receptacle containing water.

It is a further object of the invention to provide a stirrup pump comprising a liquid-containing casing having a discharge means at its upper end, a pump cylinder secured to said casing and a bracket secured to said casing holding a stirrup support and also a guide means for the plunger rod of said pump.

These and other objects and advantages of the invention will be fully set forth in the following description made in connection with the accompanying drawings in which like reference characters refer to similar parts throughout the several views and in which—

Fig. 1 is a view partly in side elevation of said device, some parts being broken away and others shown in vertical section;

Fig. 2 is a central vertical section through the discharge end of said device;

Fig. 3 is a view in side elevation of the plunger rod and handle used, some parts being shown in vertical section;

Fig. 4 is a horizontal section taken on line 4—4 of Fig. 5 as indicated by the arrows;

Fig. 5 is a vertical section taken on line 5—5 of Fig. 4 as indicated by the arrow;

Fig. 6 is a view partly in side elevation and partly in vertical section through the discharge nozzle used;

Fig. 7 is a horizontal section taken on line 7—7 of Fig. 5 as indicated by the arrows; and

Fig. 8 is a partial view in side elevation of a portion of a deflector used.

Referring to the drawings a fire extinguishing device or pump is illustrated comprising a casing 10. While this casing might be variously formed, in the embodiment of the invention illustrated it is shown as an elongated cylinder. Said cylinder has a bottom 10a closing its lower end and is provided with a closed top 10b. A projection 10c projects centrally from top portion 10b and is externally threaded. Portion 10c is constructed and arranged to receive the female connection 9 on an ordinary standard garden hose 8 com-

monly used as shown in Fig. 8. A tube 11 is disposed in casing 10, the same extending to substantially the bottom of said casing and having an open lower end. Said lower end is shown as extending in a diagonal plane. Tube 11 extends upward and through the projection 10c and to a point some distance thereabove. Said tube is provided at its upper end with an enlarged semi-spherical head 11a adapted to be embraced and form a connection for an elastic hose 12 which will be of considerable smaller diameter than the ordinary garden hose. A pump cylinder 13 is provided and extends along one side of casing 10 substantially parallel thereto and will be secured to said casing in some suitable manner as by soldering or welding. Pump cylinder 13 has an open lower end across which extends a screen 14. A bottom wall or diaphragm member 15 extends across pump cylinder 13 some distance above screen 14 and is shown as having a cylindrical flange 15a which will be secured to cylinder 13 in any suitable manner as by soldering or welding. Member 15 has a central opening 15b therethrough about which projects downwardly an annular flange 15c. The top portion of member 15 about opening 15b forms a valve seat and a valve 17 is provided comprising an annular washer-like portion 17a of rubber, leather or similar material and a member 17b of circular form having a depressed central portion extending into the central opening of portion 17a. A plurality of strips or prongs 18 are secured to the bottom of the depressed portion of member 17b and project downwardly through opening 15b. As shown, these members 18 are connected at their upper ends to a flat or horizontal portion which is welded or soldered to member 17b. Each member 18 has a portion 18a which extends outwardly substantially horizontally or transversely of the central axis of opening 15b. A terminal portion 18b on each of the prongs 18 inclines downwardly and inwardly toward said axis, said portions 18b having their ends disposed in a circumference which is smaller in diameter than the diameter of opening 15b. Casing 10 and pump cylinder 13 have a communicating opening in their adjacent walls in which is disposed a thimble 19. The side of said thimble 19 in casing 10 forms a valve seat and a valve 20 is provided thereon which is of identical construction with the valve 17 already described. Valve 20 has secured thereto and extending through the opening in thimble 19 a plurality of prongs 21 similar in construction to the prongs 18.

already described. A plunger rod 22 is provided for pump cylinder 13, the same being in the form of a tube and said tube has secured in its lower end a plug 23. A cup-like member 24 has a cylindrical hub embracing and secured to rod 22, the same also having an outer cylindrical flange 24a. Another cup-like member 25 is provided having a central cylindrical hub also embracing the rod 22. Member 25 has an outer annular cylindrical flange 25a, and is also provided with an end portion 25b. A headed screw 26 extends through end portion 25b and into the plug 23 thus holding member 25 in place. A cup washer 28 of leather or similar material extends around and across the end of cup member 24 and a similar washer 29 extends around cup member 25. Said washers 28 and 29 are oppositely disposed and their annular or cylindrical portions engage the wall of cylinder 13. Said washers with their adjacent parts thus form a plunger for rod 22. Rod 22 extends upwardly and through a guide member 30 secured in a bracket 31 to be later described. A washer 32 having a cylindrical hub 32a is secured to rod 22 in any suitable manner as by a screw 33 and forms a stop for the downward movement of rod 22. A similar washer 32 is secured to rod 22 some distance below the first mentioned washer 32 and forms a stop for rod 22 in its upward movement. It will be noted that washers 32 have their hub portions oppositely disposed. Rod 22 at its upper end extends through and is secured to a tube 27 forming a handle for said rod 22. It will be noted that the upper end of tube 22 is open at the top of handle or tube 27. A stirrup member or support 34 is provided, the same having a horizontally extending lower portion 34a and an offset upwardly extending standard 34b. Bracket 31 is in the form of a pair of straps which extend and embrace cylinder 10 at one end, the same having interlocking connected portions 31a at one side of said cylinder. The straps designated 31b thus project at the opposite side of casing 10. Member 30 is held between straps 31b and said straps are bent to provide hook-like portions 31c at their ends between which the standard 34b extends. It will be noted that standard 34b is somewhat curved in transverse cross section as shown in Fig. 3. A screw 35 extends through and between straps 31b having one end threaded in one of said straps and has oppositely extending wings at one end to form a thumb screw. A strap 36 is provided which extends between straps 31b, the same being formed of some flexible material such as closely woven fabric. Said strap has an eyelet or grommet 37 secured therein through which screw 35 extends. Strap 36 is in practice provided with a buckle and the usual perforated end cooperating therewith, said buckle not being shown.

A nozzle member is provided comprising a body 38 having a cup-like portion at one end internally threaded so as to be similar to the female connection on an ordinary garden hose and thus to be connected to the male connection 39 on such a hose 8. A tube 41 extends through and is secured in member 38, the same projecting somewhat beyond member 38 and being provided with an enlarged semi-spherical end 41a to which the smaller hose 12 may be connected as shown in Fig. 1. Tube 41 extends some distance from member 38 and has secured thereto and surrounding the same adjacent its end a cup-like member 41b having its open end and annular

rim projecting outwardly. A strip 42 is secured at one end to the side of tube 41 by a screw 43, the same extending alongside of said tube and diverging therefrom for the greater portion of its length. Strip 42 is bent toward said tube at its upper end and passes through a slot 41c formed in the end of cup member 41b. The upper end of strip 42 is somewhat tapered or pointed as shown in Fig. 6 and the extreme end of said tapered portion is given a slight bend 42a. The tube 41 is shown as contracted somewhat at its discharge end and the end portion of strip 42 normally is disposed at one side of the discharge opening in the end of said tube.

In operation, the device will be equipped with the desired hose which, as stated, may be either a small rubber hose such as shown in Fig. 1, or it may be a regular garden hose such as shown as 8 in Figs. 2 and 6. The device so equipped with the hose, which hose will be connected to the nozzle member 38 either as shown in Fig. 1 or as shown in Fig. 6, will now be placed in a receptacle containing water such as the pail 40 shown in Fig. 1. The support or stirrup 34 will engage the floor or support for receptacle 40 and can be held in place by the operator's foot. Plunger rod 22 will be reciprocated and the water in receptacle 40 will be drawn into the pump cylinder 13 as the plunger and rod 22 move upwardly. At this time valve 17 will lift and its upward motion will be stopped by the portions 18a engaging member 15. As the plunger and rod 22 move upwardly valve 20 will be held in closed position. Pump cylinder 13 thus fills substantially with liquid and when rod 22 is moved downwardly this liquid is pressed downward by the plunger. The pressure of the water thus closes valve 17 and valve 20 is opened. The movement of valve 20 into casing 10 is limited by the portions 21a on the prongs 21. The water is thus forced into the chamber in casing 10 and when this chamber is filled or partly filled the water will be forced out through tube 11 and into the hose connected thereto or the hose connected to projection 10. The operator can hold the nozzle comprising members 38 and 41 and if a solid stream of water is desired the nozzle will be operated with the strip 42 in the position shown in Fig. 6. Should it be desired to spray the water the operator will move his fingers around member 42 and will move the same inwardly over the discharge opening in tube 41. A spray can thus be directed on the fire. With the incendiary bombs used in air raids the metal magnesium is used. This can be better extinguished by the use of a spray thereon than by directing a solid stream of water on it. With the nozzle shown and described a solid stream or spray can be had at will. The device can be easily carried on the arm by means of the looped or closed strap 36. It will be understood that the screen 14 will act to keep solid particles from entering the pump. In case of emergency the device could be placed right in the bathtub and stirrup portion 34a would then engage the bottom of the tub and be submerged in the water.

All parts of the device are so constructed that they can be made of iron or steel and easily galvanized. The casing 10 and the pump cylinder 13 can be galvanized inside and out and this will be done before the ends of casing 10 are closed. With the pump rod 22 having an open end this rod can also easily be galvanized inside and out. The same will be true of the tubes 11

and 41 as well as the parts attached thereto. By means of screw 35 the strap and standard 34 can be readily assembled or very quickly detached if desired.

From the above description it will be seen that I have provided a very simple and efficient fire extinguishing device or stirrup pump. As described, the same can be used with a smaller hose or it can be quickly attached to an ordinary garden hose. The latter is usually available in most residences. The structure is simple and compact and comprises few parts. The device has been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the parts and combinations of parts disclosed and defined in the appended claims.

What is claimed is:

1. A fire extinguishing device having in combination, a casing having a liquid containing chamber, a pump cylinder disposed at one side of said casing, said casing and cylinder being secured together adjacent their lower ends, a bracket embracing said casing adjacent its top and extending to one side thereof, a plunger rod 30 for said pump cylinder, guide means for said pump rod carried in said bracket, a stirrup support at one side of said pump cylinder having its upper end secured in said bracket, said casing having a discharge tube at its upper end, and a strap for carrying said device extending around said bracket and having an eyelet therein and a tightening screw in said bracket extending

through said eyelet and adapted to tighten said bracket on said stirrup support.

2. A fire extinguishing device having in combination, a casing having a liquid containing chamber therein, a pump cylinder at one side of said casing and secured thereto, a bracket extending about said casing and having spaced portions projecting at one side thereof, a plunger rod for said pump cylinder, a guide for said rod carried in said bracket, a stirrup support for said pump having a standard disposed between said projecting portions of said bracket and a thumb screw extending through and between said projecting portions and threaded into one of the 15 same for tightening the same about said standard.

3. A fire extinguishing device having in combination, a casing having a liquid containing chamber therein, a pump cylinder at one side of said casing and secured thereto, a bracket extending about said casing and having spaced portions projecting at one side of said casing, a plunger rod for said pump cylinder, a guide for said rod held between said portions, a stirrup support for 20 said pump having a standard, said portions having oppositely disposed recesses formed therein, said standard being held in said recesses and means for moving said portions toward each other to clamp said standard therebetween.

4. The structure set forth in claim 3, said last mentioned means comprising a thumb screw extending through one of said portions and threaded into the other, a strap for supporting said device extending between said portions, the same 25 having means therein through which said thumb screw passes for securing said strap to said device.

HENRY E. BRANDT.
